SKATE CLAMP

Albert A. Tolotti, Reno, Nev.

Application May 9, 1947, Serial No. 747,033

4 Claims. (Cl. 280—11.31)

1

This invention relates to skate clamps and, more particularly, to clamps which are designed to be attached to the plate of a skate for clamping the skate upon an ordinary street shoe, which is provided with soles sufficiently rigid to support the skates.

Although a great many devices have been tried for clamping skates upon shoes, in almost every instance it has been found that in practice these clamping means are deficient for some reason or other. It frequently happens that the clamps are so designed that although initially tight, they readily become loosened during use. It has also been found that because of the fact that many clamps depend upon screw threads of relatively small diameter for their tightening action, these screw threads become jammed with ice on some occasions or perhaps become inoperable because of rust or dirt. Moreover, clamps heretofore proposed generally depend upon the skill of the operator in affixing the clamp to the sole of a shoe. Such clamps are positive in action and when undue stress is used in the clamping operation, the shoe soles are damaged unnecessarily and undue strain is placed upon the clamps. While it is necessary that skate clamps be sufficiently rigidly attached to the sole of a shoe, it is desirable that the clamping action be limited to the gripping action required in order to prevent damage to the sole of a shoe. Also, all of the prior clamping devices known to me have been so designed that their manufacture has been difficult and in many cases relatively expensive, so that a considerable portion of the cost of the skate lies in the cost of the clamp.

It is one object of this invention to provide a skate clamp that will overcome the above difficulties.

Another object is to provide a skate clamp of a new and improved design consisting of a simple structure which provides the required clamping action upon the sole of a shoe and so constructed that it can be readily adjusted without the use of a key or other tool.

Another object is to provide a skate clamp that will be sufficiently resilient in its clamping position to permit its use on shoes having soles of different dimensions without impairing the effectiveness of the clamp.

A further object is to provide a skate clamp having the above characteristics whereby the clamp may be readily released from the sole of a shoe by simultaneous operation of clamping elements engageable with opposing sides of a shoe sole.

2

A further object is to provide in a skate clamp having the above characteristics novel resilient means for exerting a predetermined clamping action of the clamp upon the sole of a shoe.

5 The above and other objects will be made apparent throughout the further description of the invention when taken in connection with the accompanying drawings wherein like reference characteristics refer to like parts. It is to be distinctly understood that the drawings are not a definition of the invention but merely illustrate certain exemplary forms by means of which the invention may be effectuated.

In the drawings:

15 Fig. 1 is a bottom view of the forward portion of a skate plate showing one embodiment of the present skate clamp in released position.

Fig. 2 is a view similar to Fig. 1 showing the skate clamp in clamping position.

20 Fig. 3 is a sectional view taken along the line III-III of Fig. 1.

Referring to the drawings, the numeral 10 indicates a forward portion of a skate plate having disposed on the bottom of the plate a pair of 25 guide members 11 and 12. The guide members 11 and 12 are placed adjacent the opposite edges of the sides of the plate 10 at substantially where the ball of a foot would rest. Each of these guides 11 and 12 has its ends 13 and 14 fixed to the opposing surface of the plate 10 and is formed to provide a recess through which the clamps 15 and 16 are slidably mounted. The outer ends of the clamps 15 and 16 are each provided with upturned jaws 17 and 18 for engaging the cooperating edge of the sole of a shoe. The inner end of clamp 15 terminates in an offset flange 19 to which one end of a spring 21 is connected as shown at 22.

The inner end of flange 16 terminates in a 40 downwardly extending flange 23, the latter terminating in an inwardly extending flange 24, the free end of the flange 24 being connected to to one end of a spring 25 as shown at 26. Means is provided centrally of the plate 10 for controlling 45 the tension on the springs 21 and 25 for clamping or releasing the jaws 17 and 18 with respect to the cooperating edges of the sole of a shoe. This means consists of an elongated member 27 spaced from the plate 10 by tubular spacing member 28 and turnably fixed with respect to the plate 10 by means of a bolt or brad 29 extending through an opening 31 centrally of the plate 10, the tubular member 28 and a central opening 32 provided in the member 27.

50 55 The inner end of the spring 25 is connected to

a projection 33 integral with one end of the member 27 as shown at 34. The inner end of spring 21 is connected to the free end of a lever 36 as shown at 37, the other end of the lever 36 being rigidly fixed adjacent one end of the member 27 as shown at 38. Finger grip members 41 and 42 are provided in order that an operator may rotate the member 27 for exerting tension of the springs 21 and 25 by turning the member 27 clockwise or releasing the tension on the springs 21 and 25 by turning the member 27 counterclockwise. A stop member 40 projecting from plate 10 cooperates with an edge of member 27 to maintain said member and associated springs 21 and 25 in locked position.

The member 27 is provided with an upstanding flange 42 spaced from the longitudinal axis of member 27, the flange 42 being at the extremity of an extension 43, thereby preventing such gripping member 42 from contacting spring 25 when the clamp is in locked position.

While I have illustrated and described certain forms of the present invention, it will be now understood by those skilled in the art that certain changes, additions, modifications and substitutions may be made in the exemplary forms illustrated and described without departing from the spirit and scope of the appended claims.

I claim:

1. A clamp device for a skate having a bottom plate for attachment to a shoe comprising: a pair of clamps having jaws for engaging the opposite sides of the sole of a shoe, an elongated member pivotally supported by said plate and intermediate said clamps, a pair of springs connecting said clamps with opposite ends of said member, and means for rotating said member to cause the springs to urge said clamp toward one another and into clamping relation with the sole of the shoe.

2. A clamp device in accordance with claim 1 wherein an over-center means is provided for maintaining the device in clamping position.

3. A clamping device for attaching a skate having a bottom plate, to a shoe, comprising: a pair of clamping elements slidably mounted on said plate for engaging opposite side edges of a sole of a shoe; a lever pivotally mounted on said plate between said clamping elements; a spring connected to the inner end of each of said clamping elements; and means connected to said pivoted lever member for varying the effective force of said springs on said clamping elements.

4. In a clamping device for attaching a skate having a bottom plate, to a shoe, the combination of: a pair of clamping elements slidably carried by the bottom plate for engaging the opposite side edges of the sole of a shoe; an elongated member pivotally carried by said plate intermediate said clamps; a pair of springs connecting said clamps with opposite ends of said elongated member; finger grip elements carried by said elongated member for rotating said member; and a stop carried by the bottom plate for cooperative engagement with one edge of said elongated member to releasably hold the same in locked position.

ALBERT A. TOLOTTI.
